ATTORNEY

UNITED STATES PATENT OFFICE.

GRACE T. BOMGARDNER, OF LOS ANGELES, CALIFORNIA.

DESIGN FOR A WOMAN'S BLOUSE.

53,234.

Specification for Design.

Patented Apr. 29, 1919.

Application filed April 1, 1918. Serial No. 226,118. Term of patent 3½ years.

To all whom it may concern:

Be it known that I, GRACE T. BOMGARDNER, a citizen of the United States, residing at Los Angeles, in the county of Los Angeles and State of California, have invented a new, original, and ornamental Design for a Woman's Blouse, of which the following is a specification, reference being had to the accompanying drawing, forming part thereof.

The figure is a perspective view of my new design.

I claim:

The ornamental design for a woman's blouse, as shown.

GRACE T. BOMGARDNER.

Witnesses:

W.M. M. RHEEM,
MARION KEMBLE.
